OF DAYTON, OHIO, A CORPORATION OF OHIO

GAS GENERATING APPARATUS

Application filed December 14, 1925. Serial No. 75,316.

This invention relates to gas generation and more particularly to the generation of gas for domestic or household use.

One of the principal objects of the invention is to provide for the production and distribution of combustible gas, particularly for domestic or household use, and for remote control of the generation and distribution.

10 Another object of the invention is to provide apparatus for producing such combustible gas in which the generation and distribution can be controlled from one or more distant points.

15 Another object of the invention is to provide a gas generating and distributing system of this character in which the generation and distribution of the gas is automatically controlled during gas making operation.

20 Still another object of the invention is to provide such gas generating and distributing apparatus in which the generation and distribution of the gas will be automatically controlled to prevent improper functioning of the apparatus.

25 Other objects and advantages of the invention will be apparent from the description thereof as set out below when taken in connection with accompanying drawings.

In the drawings in which like characters of reference designate like parts throughout the several views thereof:—

Fig. 1 is a somewhat diagrammatic view, 30 in elevation, of a gas producing and distributing system embodying this invention;

Fig. 2 is a view, generally in elevation, of the apparatus shown in Fig. 1 and taken at right angles thereto along the line 2—2 of Fig. 1;

Fig. 3 is a vertical sectional view, with parts in elevation, of parts of the blasting and control elements taken along the line 3—3 of Fig. 1;

Fig. 4 is a vertical sectional view, at right angles to Fig. 3, taken along the line 4—4 of Fig. 3;

Fig. 5 is a view, diagrammatic in character, of the blasting and control mechanism, and comprising a wiring diagram of

the control mechanism, forming a part of the apparatus shown in Fig. 1;

Fig. 6 is an enlarged somewhat diagrammatic elevational view showing one element of the control mechanism;

Fig. 7 is a vertical sectional view similar to Fig. 3, and showing a modification thereof;

Fig. 8 is a diagrammatic view similar to Fig. 5 but comprising the form of control mechanism shown in Fig. 7;

Fig. 9 is a diagrammatic view of still another somewhat modified form of control; and

Fig. 10 is an elevation of a preferred form of producer with parts broken away and in section to illustrate the construction thereof.

While apparatus for generating so-called producer gas is of course old and well known, the conventional forms of producers heretofore known are totally unsuited to the generation of gas for domestic or household use. For one thing the plants of this character heretofore generally used have been of such large capacity that none of them has been capable of operating under such small load as constitutes the normal demand of the average house. In addition producers of the character heretofore generally known are of little practical value so far as solving the problem of furnishing gas for domestic or household use; for very peculiar problems arise in connection with such a plant. Among other defects, the heretofore generally known producers fail completely in the matter of furnishing gas immediately, or with a very short waiting period, while at the same time providing for efficient operation; they also fail completely in the matter of controls whereby the plant may be operated from a distance; and they also fail completely in the question of controls arranged to safeguard the user so that, for example, asphyxiation, gas poisoning, or dangerous explosions will not result if the operator carelessly leaves a burner valve open, or any other leak in the gas line occurs, or like abnormal operating conditions arise.

The form of apparatus herein shown as constituting

tuting a preferred embodiment of the invention is arranged to entirely eliminate all of the above referred to defects, and others also, and to provide a very small, compact, inexpensive, efficiently and effectively operating gas generating system for household use, which is adapted for remote control and is substantially fool-proof in that its operation is extremely simple and the starting of the plant cannot take place if a valve has been left open or any other substantial leak in the line is present; or other improper conditions exist.

The invention forming the subject matter of the present application is quite analogous to, and in some respects an improvement on, the invention shown in the copending application of Harry F. Smith, Serial No. 469,976 filed May 16, 1921.

Fig. 1 shows in elevation, and somewhat diagrammatically, a domestic or household gas generating system embodying the invention. This system comprises a gas producer or generator which is designated generally by the numeral 10. This producer may be of any suitable character, but the conventional type of producer heretofore known has not been found at all satisfactory or capable of functioning when constructed in the small sizes which should be used for such domestic or household use. While any suitable sort of producer may be used, therefore, nevertheless applicant's experience has shown that the producer should be one of the character which he has developed, such a producer for instance as is shown in his copending application, Serial No. 570,972 filed June 26, 1922. Such a producer or generator comprises generally a base member designated generally by the numeral 11 which supports a shell 12, the shell being without any conventional lining but adapted to contain fuel throughout its entire width, to whatever depth the fuel may be introduced. The fuel bed is supported upon the base 11, and is introduced through the fuel feeding mechanism 13, which comprises a rotatable pocketed measuring device having the handles 14 attached thereto, adapted to introduce the fuel in predetermined charges without allowing the ingress of air to the producer or the escape of gas from the producer. The gas passes off through a centrally arranged offtake 15, as clearly described in the copending application just above referred to, the blast of air and moisture being introduced through an opening 15' in the base in the manner also described in that copending application. The saturator 16 is disposed in the base and receives its heat from the heated fuel bed and also from the offgoing gas passing off from the producer through the passage 17 in the base to which the offtake 15 is connected so that during operation the rate of vaporization is substantially constant for a given

load. Air passes into the saturator 16 through an intake 18 opening to atmosphere, the air passing into the ash pit 19 through a passage 18', and steam generated in the saturator 16 passing into the ash pit 19 through an opening 19', the blast of mixed air and steam then passing through the blast inlet opening 15' into the fuel bed. The passage of blast through the fuel bed is controlled so that the zone of incandescent fuel is at all times surrounded by a zone of inactive or unburned fuel which serves to heat-insulate the active zone from the shell and thus cut down the heat losses from the active or burning zone of the fuel bed through radiation losses from the shell into the atmosphere to an unobjectionable amount. The hot generated gases pass from the fuel bed through the base 11 and thence through a coil or radiator 20, which may consist of an ordinary section of steam radiator such as is used for steam radiating coils in general household use, where it is cooled sufficiently to prevent damage to the material of the purifier 32 which removes impurities from the gas.

The gas generating system may be either pressure operated or suction operated, as desired. But preferably it is suction operated, the entire gas generating system being thus under partial vacuum which prevents the possibility of the leakage of gas from the gas generating system into the surrounding atmosphere. In order to provide the suction a suitable exhauster 25 is provided. This exhauster may be of any conventional character, but very satisfactory results have been secured with a blower of the character generally shown in the drawings, which blower comprises a centrifugal fan or impeller having radial blades revolving in a volute casing. Not only does such a blower efficiently and satisfactorily provide suitable suction for blasting the fuel bed in the producer and for forcing the generated gas under adequate pressure to the delivery line, but it is quiet in operation, and lends itself nicely to control during operation. This blower is driven by a suitable operating or driving means illustrated as an electric motor 26, and functions to cause a suction for drawing a current or blast of air and moisture through the fuel bed to cause the generation of gas, this being hereinafter termed "blasting" for purposes of easy description, and for forcing withdrawn gas through a delivery main or pipe 27 to suitable work devices. As illustrating a suitable work device the numeral 28 designates generally a conventional gas stove such as is used for household cooking. The inlet to this blower, which is designated by the numeral 30, is connected to the outlet of the producer 10, the radiator 20 and gas puri-

fier 32 being interposed between the producer and the blower inlet.

The cooled gas leaving the radiator 20 under the action of the blower passes into the purifier 32 where the impurities are removed. This purifier is generally of the same character as that shown in the copending application of Harry F. Smith, Serial No. 570,972, filed June 26, 1922, in which 5 gas to be purified is passed through a layer of finely divided charcoal or the like, the sizes of the particles of charcoal being of dimensions which are proportionate to the dimensions of particles of the impurities to be removed. While the general form of 10 purifier is not of any particular importance so far as this instant invention is concerned so long as the purifier is effective to remove the impurities to a sufficient degree, nevertheless its form is shown generally. The 15 purifier comprises a cylindrical metallic shell 33 which has mounted coaxially therein a cylindrical screen covered by a filter cloth of wool or similar material the screen 20 and covering filter cloth being designated generally by the numeral 34. In the modification shown the filter cloth is on the inside of the screen and during operation has maintained thereon a thin layer of finely divided 25 charcoal, or the like. The gas to be purified passes from the radiator into the cylindrical shell inside of the screen, thence through the screen and coated filter cloth to the exterior of the screen and thence outwardly 30 through the passage 30 to the inlet of the blower. As the gas passes through the filter cloth the impurities therein are deposited upon and within the layer of purifying material on this cloth. These impurities 35 will of course vary with the character of the fuel used in the producer, and the purifier shown and described herein is primarily adapted for cleaning gas generated from charcoal or the like. Where gas is generated 40 from bituminous coal the quantities of tar produced are very much larger than in the case of gas generated from charcoal and consequently a different type of purifier should 45 preferably be used such, for example, as the commercially well-known glass wool tar extractor. But with gas generated from charcoal the impurities consist in part of 50 solid particles of charcoal dust and the like, associated with tar and lamp black and these 55 are removed by this form of purifier. Purifiers of types heretofore known and used by others will not remove a sufficiently large 60 percentage of the impurities in the gas to give satisfactory operating conditions when the gas is intended for general household use. But as stated above a layer of finely 65 divided charcoal, the particles of which are of dimensions approaching the dimensions of the impurities to be removed will show a very high effectiveness in cleaning, cer-

tainly not less than 99.5% of the impurities being removed, and generally considerably more than this. The layer of finely divided charcoal should be at all times maintained on the cloth during operation. If not present a considerable part of the impurities would be removed by the cloth alone, with the deposit of impurities upon and within the interstices provided by the fibres of the screen cloth; but these impurities would so 70 clog the interstices of the cloth as to obstruct and even prevent subsequent passage therethrough of the gas to be cleaned. This permanently destroys the effectiveness of the cloth and necessitates its replacement. And after once so clogged the cloth may not thereafter be used. But if the cloth is, at the beginning of the cleaning operation and from time to time thereafter as needed, 75 dusted or coated with charcoal dust or the like, the impurities collect on the layer of charcoal and do not penetrate the cloth fibres—so that long and effective life of the cloth ensues. The means shown in the drawings for accomplishing this coating comprises a closure for the shell 33 comprising 80 a feeding mechanism 35 somewhat similar to the fuel feeding mechanism 13 which is arranged to introduce predetermined charges of finely divided charcoal into the shell. 85 The gas generating plant having been started a quantity of this finely divided charcoal is introduced into the shell, into the gas stream, this dust being deposited upon the inner surface of the filter cloth and within 90 the surface fibres to form a filtering layer which itself thereafter constitutes the filtering medium. The liquid impurities in the gas generated from charcoal tend to clog 95 the layer of dust upon the screen, and to thus undesirably increase the resistance to flow through the purifier. In order to provide for overcoming this condition the layer of impurities may be removed by a scraper and an additional charge of finely divided 100 charcoal introduced to build the filtering layer back up to the desired thickness, which is a small fraction of an inch, it having been found that with purifiers of this character the zone of actual cleaning is confined to a quite thin layer upon the surface. The material scraped from the filter cloth falls into the bottom of the purifier where it may be removed from time to time through 105 the door 37.

The gas drawn from the purifier by the blower is forced from the blower casing through the outlet pipe 40, under any desired pressure, the pressure ordinarily in household use being only a few inches of 110 water. Associated with this outlet pipe is suitable control valve mechanism by means of which it may be connected either to the delivery pipe 27 or to the vent pipe 42. Normally, when the plant is not in operation this 115

120

125

130

valve mechanism is positioned to close the delivery line and to connect the outlet of the producer to the vent pipe. If a producer of this kind is operated continuously it will of course furnish combustible gas continuously but this tends to unnecessarily increase the cost of operation since when none of the work devices are in use the generated gas would be wasted to atmosphere.

Consequently the gas generating system shown herein is adapted for what may be called "intermittent operation" in that the plant operates to generate gas, generally, only when gas is being used at a work device. Consequently if the plant has been standing idle,—"standing by" as it is called,—it may be necessary to blast the fuel bed at a comparatively rapid rate for a brief period in order to bring it up to good gas making condition. During starting of the plant, and during any such blowing up period, the blower should be connected to a vent, as otherwise the products of the combustion during the blowing up period would be forced into the house. Generally the gas producer or generator will be located in the basement of the house, or in some outhouse, while the work devices, such as the stove illustrated diagrammatically, the hot water tank, the gas grates and the like, will be located in the living quarters of the house; so that the gas producer and the work devices may be located many feet apart. This invention not only provides control mechanism for the valve which connects the blower to the vent or to the house line, but in addition provides suitable control mechanism whereby operation of the gas generating plant may be effected and controlled from a distant point, such for instance as a suitable control switch 45 located at the kitchen stove, or some similar place, such control being hereafter termed "remote control." In actual practice this switch is preferably attached directly to the manifold 46 along the front of the stove, within which are located the various individual burner valves which control operation of the stove.

The outlet pipe 40, of the blower is attached to the inlet opening 50, of the valve casing 51, which casing is divided by an upstanding circular partition 52 into two compartments 53 and 54. The compartment 53 is connected through the inlet opening 50 to the outlet 40 of the blower, the compartment 54 being connected through the restricted opening 55 to the house delivery line 27. Inasmuch as the centrifugal blower delivers a definite maximum pressure at maximum operating speed the restricted opening 55 determines the maximum amount of gas which may pass into the house line during operation. Positioned within the compartment 54 is an upstanding

hollow guide 58, which has slidably mounted therein the stem 59 of the disc valve 60, which valve is adapted in one position to seat upon the upper edge of the partition 52. The upper end of the casing 51 is open, and is attached, in gas tight connection, to the lower end of the casing 65, which has an opening or passage 66 in the lower face thereof which opens into the open upper end of the casing 51. This opening 66 is provided with a downwardly extending flange or seat 67, adapted to cooperate with the upper face of the valve 60. This open casing 65 has a chamber 68 therein, which is connected to the passage 66. This chamber 68 is also connected by means of the passage 69, with the vent pipe 42. Positioned within the chamber 68 is an electromagnet designated generally by the numeral 75, which comprises generally a spool shaped core 76, having a suitable winding 77 thereon, this magnet being adapted when energized to lift the valve 60 against the seat 67 to close connection between the inlet passage 50 and the vent pipe 42. When the magnet is not energized the weight of the valve 60 causes it to seat against the upper edge of the partition 52, thus opening connection between the inlet opening 50 and the vent pipe 42 and closing connection between the inlet opening 50 and the house line 27. When the valve is held in uppermost position and against the seat 67 the inlet passage 50 is disconnected from the vent pipe and is connected to the house line 27, so that gas under suitable pressure is fed to that line. Within the passage 69 is a restricted opening 70 which functions with respect to the vent pipe just as does the opening 55 with respect to the house line.

For effecting the desired control of the gas generation the switch 45 may be made as a three-button switch, as shown diagrammatically in Fig. 5. This switch in practice is preferably of the press button type, and each button opens or closes contact through a line switch. As shown diagrammatically in Fig. 5 there is a switch 80, which is used to close the proper circuits to cause the blower to start operating to blast the producer; a second switch 81 which is adapted to switch connection of the producer from the vent pipe to the house line after the blowing up operation has proceeded long enough to properly condition the active zone of the fuel bed; and a switch 82 which stops operation of the blower and thereby shuts down the plant.

When it is desired to start the operation of the producer, presuming that it has been standing by, or that it is starting from cold and the fire is being freshly kindled therein from burning paper or the like placed in the ash pit of the producer, the button of the switch 80 is pressed to close this switch.

One pole of this switch is connected by means of the conductor 84 to one terminal of the battery 85 or to any other source of electrical energy. If desired the electrical controls may be arranged to plug into the ordinary household electric line, with the use of suitable conventional transformers. It is only needed, therefore, that the switch 80 have one pole thereof attached to the source of electrical energy. The other pole is connected by means of the conductor 86, to one terminal of an electromagnet 87, the other terminal of which magnet is connected by means of the conductor 88 to the other pole of the battery 85, or other source of electrical energy. Closing the switch 80 energizes the magnet 87 and this in turn attracts the armature 90 which is pivotally mounted adjacent the end of the core of the magnet 87. One end of this armature 90 is connected to one side 91 of the house lighting line, the other end being provided with a contact 92 which cooperates with a corresponding contact 93, the contact 93 being connected by means of the conductor 94 with an electrode 95. This electrode is positioned within a suitable container 100, preferably of glass, which container comprises an inverted tube, closed at the top, within which the electrode 95 is mounted, and open at the bottom, the bottom extending down into a glass container 101, which is supported upon the top of the casing 65. This container holds a considerable quantity of electrolyte of any suitable character which is designated generally by the numeral 102, and the lower open end of the tube 100 extends to terminate within the electrolyte and below the end of the electrode 95. In practice it has been found that very satisfactory results have been obtained where this electrolyte consists of very dilute sulphuric acid. A thin layer 103 of paraffin oil or the like is preferably floated on top of the electrolyte to prevent evaporation. Also positioned within the container 101 is a second electrode 105. Both these electrodes may be composed of any material which will stand up sufficiently under operation; but very satisfactory results have been secured with electrodes consisting of carbon. This second electrode extends down below the bottom of the inverted tube 100 and into a layer of crushed or granulated carbon 106, which serves to greatly increase the surface area of this electrode and thereby serves to insure good electrical contact between the electrolyte 102 and the electrode 105. This electrode 105 is connected by means of the conductor 110 to one pole of the blower operating motor 26, the other pole of which is connected by means of the conductor 111 to the other side of the house lighting line. The two electrodes and the cooperating electrolyte therefore function as an auxiliary switch or contact member within the motor circuit, the contacts 92-93 constituting the main switch. Leading off from the top of the tube 100 is a passage 115 which opens into the inlet passage 50 of the valve casing. 70 When the plant is not operating the valve 60 will be positioned upon the seat at the top of the partition 52, with open connection between the inlet 50 and the vent pipe 42. At the same time the pressures inside and 75 outside of the tube 100 will be balanced since the inside of the tube is connected to atmosphere through the tube 115 and vent 42. So when the switch 80 is closed to start operation this will close the circuit through 80 the magnet 87, which will swing the armature 90 to close the contacts 92 and 93. At this time both the electrode 95 and the electrode 105 will be immersed in the electrolyte and consequently the motor circuit will immediately be closed to cause operation of the blower. Because of the positioning of the valve 60 the gases fed from the blower will pass freely through the vent to atmosphere, the house line remaining closed off 90 from the blower. So long as the switch 80 is held closed and the valve 60 remains seated on the partition 52 with the blower outlet connected to vent the blower will continue to operate to blast the fuel bed. 95

Provided in the partition 52 is an orifice or passage 120 which connects the chamber 53 to the chamber 54, and beneath the valve 60 when that valve is seated on the partition 52. Connected to the space 54 within 100 the valve casing is a passage 125, which leads into the bottom of a chamber 126 within the casing 127, supported above the container 101. The chamber 126 is provided with a flexible diaphragm 128, of leather 105 or other suitable material, which is held in place by means of a suitable retaining ring 129 and has a weight 130 carried thereon, which weight tends to urge the diaphragm downwardly. Mounted upon the weight is 110 an upwardly extending standard 131 which is connected to an arm 132 which is in turn attached to the pivoted armature 133, associated with the electromagnet 134. As pressure tends to build up in the chamber 115 126 below the diaphragm 128 the diaphragm is raised carrying the weight and arm 132 with it. The free end of the arm 132 has a latch member 135 associated therewith which moves behind the end of the armature 120 90, as the diaphragm moves upwardly, to latch that armature with the contacts 92 and 93 closed. As soon as this condition is realized the operator may remove his finger from the switch 80 as the motor circuit is 125 then held closed so long as the pressure within the casing 127 is sufficiently great to hold the diaphragm up.

The description of the starting operation as set out just above presupposes that the 130

house line has no leaks of any sort in it. When the blower is started gas will pass through the orifice 120 at a predetermined rate. If the house line is tight the pressure will accordingly build up quite rapidly in the house line and chamber 54 and, acting through the passage 125, will cause upward movement of the diaphragm 128, as described, to "hook up" the plant,—that is, to latch the main motor circuit contacts closed. If, however, a valve has been carelessly left open in the line, or any other leak of material size exists, the limited quantity of gas passing through the small orifice 120 will not be sufficient to cause a building up of pressure in the line and in the chamber 54 and consequently the diaphragm 128 will not be actuated to cause hooking up of the mechanism. If then the finger of the operator is removed from switch 80 the blower will not continue to operate, as described above, but will immediately stop; for if the contacts 92 and 93 are not latched together by the hook-up mechanism they will be held in contact only so long as the magnet 87 is energized, and this will be only so long as the switch 80 is held closed. And the plant will refuse to operate in the regular manner so long as any substantial leak exists in the house line; which renders it "fool proof", for the arrangement described makes it impossible for anyone to so operate the plant so long as leakage occurs. Also it inevitably indicates to the operator that something is wrong.

If no leak is present the hook-up mechanism will function after a short interval,—normally a few seconds,—to latch the main motor contacts shut. In order that the operator, located at a distance from the plant, may know that this condition exists indicating mechanism is provided. As shown in Figs. 1 and 5 this mechanism may consist of a pressure gauge 137 connected in the house line at some convenient and readily seen place, such as a portion of the house line adjacent the stove and operating switch fixture 45. This gauge need only have means for indicating a pressure condition which corresponds to the pressure required for causing the hook-up mechanism to function. In actual operation, therefore, the operator merely presses the button to close switch 80 and holds this switch closed until the indicator 137 shows a predetermined indication,—which may be movement of a hand to a given point, movement of a column of liquid to a given point, flashing of a light, or the like,—which shows that the hook-up mechanism has functioned. He can then remove his finger and the motor will continue to operate to blast the fuel bed and waste to atmosphere the resulting gases,

until the generated gas is of such character as to be satisfactorily combustible. This may be determined by testing at the producer, a small valve controlled test burner 139 being normally provided for this purpose. Or the plant may be actuated to turn the generated gas into the house line so that the test may be made at one of the burners of the stove. If such a test at the stove shows the gas to be suitably combustible the plant may be allowed to continue its operation. If not the gas may be again diverted into the vent pipe and the blowing in continued until gas of desired quality is obtained.

When it is desired to turn the gas from the vent into the house line, the indicator 137 having shown a pressure sufficient to cause the hook-up mechanism to have functioned to lock the main motor contacts closed the operator presses the button to close switch 81. This causes energizing of magnet 75, the current flowing from the battery 85 through the conductor 84, across the switch 81 along the conductor 138 connected to that switch and thence through the winding of the magnet, the direction of flow of the current being as desired. The magnet then lifts the valve 60 against the seat 67 to disconnect the blower from the vent pipe and connect it to the house line. The weight and proportions of the valve 60 are so arranged that when lifted against the seat 67 it will be held there by the pressure of the gas. But if the pressure beyond the restricted opening 55 falls sufficiently the weight of the valve will no longer be sustained and the valve will fall onto the partition to again connect the blower to the vent pipe. The arrangement is such that the pressure normally attained in the house line during operating conditions is sufficient to hold the valve against the seat 67; but if there is a sufficiently abnormal drop in this pressure then the valve will fall and the work devices connected to the house line will be cut off from utilization of gas until the switch 81 is again actuated to connect the house line to the blower. Thus if the plant is unduly overloaded during operation the pressure in the delivery line will drop and inadequate functioning of the work devices or overloading of the producer will thus be entirely prevented. It is thus seen that during both blowing in and gas making operations the motor circuit is controlled according to pressure conditions.

This described construction also provides another protective feature,—prevention of automatic restarting of the plant after an abnormal interruption of the current in the house line. If this current should be interrupted for an appreciable time while gas is being utilized at a work device the blower motor would stop, irrespective of the posi-

tioning of the auxiliary contacts, and consequently the flame would be extinguished at any open burner due to failure of the gas supply. If the hook-up mechanism should 5 remain undisturbed the motor would restart upon resumption of current flow through the house line and the house would be filled with gas. But this cannot happen with these controls. For when the house line current fails, 10 pressure within the house line will of course also fail, one or more burners being open. The valve 60 will then be no longer sustained and will drop onto the partition 52 to connect the blower to the vent pipe. At the 15 same time pressure beneath the diaphragm 128 will fall to atmospheric pressure and the weight 130 will drop unlatching the hook-up mechanism and permitting separation of the contacts 92 and 93. And so 20 when current flow through the house line is resumed the main motor circuit switch is open and the motor cannot start until there has been outside intervention,—such as the operator restarting in the normal manner.

25 The blower at its normal rate of operation delivers gas at such a rate that there is a tendency for the pressure in the valve casing to continue to build up. As this pressure increases it acts through the passage 115 to affect the pressure existant in the tube 100 upon the top surface of the electrolyte and forces that electrolyte downwardly and out into the container 101. As the pressure continues to build up the electrolyte is forced downwardly below the lower end of electrode 95 to break the circuit. But due to the adhesion of the electrolyte to the lower end of the electrode as the level of the main body of the electrolyte falls materially below the end of the electrode that portion in contact with the electrode is retained in contact and its surface tension then causes a progressive diminution of the cross section of the extended portion of electrolyte until it is 30 "pinched off"—as shown diagrammatically in Fig. 6. As a result the current flow is not suddenly interrupted by quick breaking of contact with the contacts within arcing 35 distance of each other;—but is choked off as the resistance builds up due to the diminishing cross section of the conducting portion of the electrolyte, and consequently objectionable 40 sparking evils and other evils normally attendant upon the breaking of a flowing current are not present as the current flow is finally interrupted at a flow which is substantially zero so far as objectionable 45 results are concerned. This action is accentuated by forming the lower surface of the 50 electrode substantially parallel with the surface of the electrolyte and of considerable extent; and further by adjusting the conductivity of the electrolyte so that the 55 "necked down" or diminished portion below

the electrode offers a rapidly increasing resistance which quickly cuts the current flow to unobjectionable proportions. When constructed as described and used with an electrolyte which wets the electrodes there will be a drop or film of the electrolyte left on the lower end of the electrode after break, and as the electrolyte rises again into contact with the drop the surface tension effects will cause substantially immediate spreading of the electrolyte into contact with the whole end of the electrode to give immediately a full, low resistance contact. However, the relative arrangement and proportioning of the parts is such that the pressure at this time is still sufficiently high to hold the latch 135 up to maintain the contacts 92 and 93 closed, and to hold the valve 60 against its seat 67. As the pressure in the delivery line rises, therefore, above a predetermined normal the current in the motor circuit is interrupted; and as the pressure falls the motor circuit will be again closed as soon as the electrolyte comes in contact with the electrode 95. Thus a continuously intermittent energizing of the operating motor will occur during use of the device, under normal gas using operations the current to the motor and operation of the blower being normally interrupted a number of times a minute with the result that the effective pressure in the delivery main 27 is maintained substantially constant. In actual operation the blower itself generally does not cease movement as it is controlled during utilization of the gas, for the contact mechanism is responsive to slight pressure fluctuations and therefore the breaking of the motor circuit as the normal pressure is exceeded is so brief that inertia will cause continued rotation of the motor and blower parts. And the practical effect is to secure a substantially uniform gas pressure, with a very accurate and simple control for motors of conventional construction and characteristics.

When it is desired to terminate operation of the device for a period the button 82 is pressed to close that switch which acts through the conductors 140, 141 and 84 to energize the magnet 134. This swings the armature 133 to move the latch 135 into inoperative position and as the magnet 87 is at this time unenergized the spring 142 will swing the armature 90 to break the contact across the contact points 92 and 93 thus stopping the blower. Of course the operation may also be stopped by cutting off all the burners, or other work devices when the increased line pressure will open the auxiliary contacts.

Pivots attached to the casing 51 (as shown particularly in Fig. 3) is a water container 150, having a depending pocket 151 into which extend two drain pipes 152 and 153 which drain off from the chambers 53

and 54 respectively any moisture which may condense in those two chambers. This water container 150 is connected by means of a flexible pipe 155 to the saturator 16 in the base of the producer, and water is supplied to this container through the pipe 156, which leads into a nozzle 157, the lower end of which opens into the container 150. Carried by the container adjacent the end of this nozzle is a valve member 158, which is moved toward or from the opening in the nozzle 157 as the container 150 swings about its pivotal supports, one of which is indicated in dotted lines at 159. The water in the container tends to swing the container about its pivotal supports in one direction. The container is provided with a projection 160 upon which is adjustably mounted the balance weight 161. This balance weight tends to counterbalance the tendency of the water to swing the container in one direction, to move the valve seat toward closed position. By means of this arrangement the positioning of the valve seat 158 with respect to the open end of the nozzle 157 varies according to the quantity of water within the container. Of course the greater the load upon the producer the more rapid the vaporization of the water in the saturator for incorporation with the air of the blast and therefore the greater the quantity of water which must flow from the container through the pipe 155 to the saturator. This pivotal mounting of the container, with counter-balancing, results in such motion of the container that the valve seat 158 is moved away from the nozzle to permit a greater flow of water when the water level falls and is moved toward the nozzle to cut down the flow of water when the water level rises.

In Figs. 7 and 8 is shown a somewhat modified form of device. In the ordinary household use the gas plant may stand idle for considerable periods, overnight for example. Ofttimes the gas is used for heating the water in the hotwater system in which case there is a continuous load on the producer and the fuel bed is thus maintained in good gas-making condition so that it immediately responds to increased load to give any desired quantity of good gas within its capacity. But where the producer stands idle for any considerable period the ignited fuel may cool below incandescence so that it may be necessary to blow in the fuel bed afresh before good combustible gas in quantities may be secured. This may make necessary a wait of several minutes before suitable gas is secured, and would also make necessary igniting kindling material in the producer itself. In order that the fuel bed may be at all times maintained in suitable condition, even during considerable standby periods, means is provided whereby the blower is automatically operated at inter-

vals to cause a short blowing in of the fuel bed to maintain it alight, this permitting remote control at all times. This means is shown in Figs. 7 and 8 in which the control mechanism is provided with a second electrode 200, which is similar to the electrode 95', but is of somewhat less length. In order to enclose these two electrodes a double tube 201 is provided which has two depending legs, one 100' which contains the electrode 95' and the other designated by the numeral 202 which houses the additional electrode 200. The upper ends of these two tubes are connected to the main body of the tube 201 by means of cement, or the like, as is shown in Fig. 7 of the drawing, for example. There is also positioned within the leg 200 of the main tube a second tube 203 which extends down below the normal standby level of the electrolyte and the interior of which is disconnected from the interior of the main body of the tube when its lower end is within the electrolyte. This tube 203 has a branch 204 extending to the outside of the main tube 201, within which is positioned a closure member having a predetermined orifice therethrough, the orifice member being designated by the numeral 205. This orifice member may be of any suitable character; but in practice a small piece of thermometer tubing functions very satisfactorily. The main part of the tube 201 is connected by means of passage 115' to the gas pressure within the valve casing as described above. During operation the tube 201 with its two depending legs 100' and 202 will be so filled with gas that the level of the electrolyte is at approximately the lower end of the electrode 95'. But when the plant is shut down or standing by the electrolyte rises within the legs 100' and 202 until it is at substantially the same level inside and outside thereof; except that as the electrolyte covers the lower end of tube 203 it traps gas therein and can rise in that tube only as the trapped gas escapes through the orifice in the member 205. And the effective area of that orifice is such that after a predetermined interval the gas will have escaped sufficiently to permit the electrolyte to move upwardly in the tube 203 to contact with the electrode 200. This electrode 200 is connected by means of a conductor 210 with the line 91' which is a circuit around the main motor circuit contacts 92-93, this arrangement being such that as the electrolyte contacts with electrode 200 the motor is energized to start the blower to cause blowing in of the fuel bed. But the motor will run for only a brief period as its operation builds up pressure within the main tube 201, which breaks the contact. This blowing in period may be of such length as desired but ordinarily is just sufficient to liven up the fuel bed and keep it

alight. The intervals between these periodic blastings will depend on the time necessary for the gas leakage from the tube 203 to permit closing of the by-pass circuit—and this depends on the size of the tube 203, the extent of necessary electrolyte rise therein, and the effective area of the orifice. In actual practice satisfactory results have been secured where these blastings occur at about five minute intervals; but the intervals between them may be regulated to suit operating conditions. Because of the normal stand-by positioning of the valve 60 the gas resulting from such periodical blasting will be discharged to the vent pipe.

In Fig. 9 is shown, diagrammatically, a modification which gives the same results as does the form of Figs. 7 and 8; but which is simpler in construction. In this figure a single large tube 225 is provided which is suitably supported from the cover 226, in gas-tight relation as is the case also in the other forms shown and described above. Extending down through the cover 226 and into the space within the tube 225 is a second tube 227, which is connected by means of the passage 115' to the outlet of the blower, as described above. Mounted in the cover 226 and extending down different distances into the space between the two tubes 225 and 227 are two electrodes 95'' and 200'. Also mounted in the cover 226 is a leak tube 204' having an orifice member 205'. The operation and function of these several elements are the same as described above. In Fig. 9 the level of the electrolyte is shown as of immediately after stopping the blower and before any appreciable leakage of gas through the leak tube 204'. In Fig. 8 the level of the electrolyte is shown as of a time when the leakage through tube 204 has just permitted the electrolyte to contact with the electrode 200 to close the motor bypass circuit. In Figs. 3, 4 and 7 the level of the electrolyte is shown as of standby period with the levels inside the tube 100 the same.

As clearly shown in Figs. 3, 4 and 5 the control mechanism is provided with means for effecting direct manual operation of the starting and stopping controls, in addition to the electrical remote control means fully described above. As shown the casing which encloses the two electromagnets which respectively effect closing of the main motor circuit contacts, and effect breaking of that main motor circuit contact, is provided with two openings through which extend arms 250 and 251, attached respectively to the armature 90 which constitutes one element of the main motor circuit contacts, and to the armature 133 which constitutes the unlatching mechanism for the main motor circuit contacts. These two arms are, as will be evident from Fig. 1 of the drawings, im-

mediately adjacent the gas producer itself, and therefore constitute means readily accessible by the operator of the producer when he is working in and about the gas producer itself. Of course the blower and the controls need not necessarily be positioned so closely adjacent the producer as shown, for they may be positioned any greater distance therefrom that might be desired. Furthermore, the controls need not be positioned immediately adjacent the blower, inasmuch as the use of the electrical elements of the controls permits of remote control from any distance. But preferably, because of simplicity in manufacture, installation and operation the producer, the purifying mechanism, the blasting means and the controls are positioned closely adjacent each other as shown. And preferably the remote control means comprises the manually controlled electric switches, as well as the manually controlled arms, so that control may be effected by either means independent of the other.

Also as clearly shown in Figs. 1 and 3, a switch control which is a duplicate of the main switch 45 is mounted immediately adjacent the control mechanism, as indicated by the numeral 260. This switch gives the same manual control of the electrical means when the operator is adjacent the apparatus set up as shown in Fig. 1 as may be had from a more remote distance through the manipulation of the switch 45. As a matter of practical operation anyone of these three manually controlled mechanisms is adequate for giving complete control of the gas generation and distribution; but for purposes of convenience the multiplicity of controls is provided. And there are times when the complete manually operated controls embodying the arms 250 and 251 are desirable because there may have been some failure in the electrical circuits controlling the main motor circuit contacts.

While the forms of apparatus herein described constitute preferred embodiments of the invention, it is to be understood that the invention is not limited to these precise forms of apparatus, and that changes may be made in either without departing from the scope of the invention which is defined in the appended claims.

What is claimed is:

1. Apparatus of the character described, comprising a gas producer adapted to contain a fuel bed of carbonaceous material, means for blasting said fuel bed to cause the generation of a combustible gas and for distributing said gas for use, power means for causing operation of the blasting means; and remote control means for controlling the operation of said power means, said control means comprising manually controlled means for initiating operation of the power

- means, manually controlled means for stopping operation of the power means, and automatic means for interrupting operation of the power means as the pressure in the 5 distributing pipe exceeds a predetermined normal and for restarting the operation of the power means as the pressure in the distributing pipe falls below predetermined normal.
- 10 2. Apparatus of the character described, comprising a gas producer adapted to contain a fuel bed of carbonaceous material, motor driven means for blasting said fuel bed to cause the generation of combustible 15 gas and for distributing said gas for use; and means for controlling the operation of said motor driven blasting means during the utilization of gas comprising a motor circuit, pressure responsive means for temporarily opening the motor circuit, and other means for permanently opening the 20 motor circuit.
- 10 3. Apparatus of the character described, comprising a gas producer adapted to contain a fuel bed of carbonaceous material, motor driven means for blasting said fuel bed to cause the generation of a combustible gas and for distributing said gas for use; and means for controlling the operation 25 of said motor driven means comprising a motor circuit, manually controlled means for closing the motor circuit, means adapted for positioning to hold the motor circuit closed during gas-making operation of the 30 producer, means for causing said holding means to move into such holding positioning, and pressure responsive means for interrupting the motor circuit without affecting the positioning of the said holding 35 means.
- 10 4. Apparatus of the character described, comprising a gas producer adapted to contain a fuel bed of carbonaceous material, motor driven means for blasting said fuel bed to cause the generation of a combustible 40 gas and for distributing said gas for use; and means for controlling operation of the blasting means comprising a motor circuit, remote manually controlled means for closing the motor circuit, means adapted for positioning to hold the motor circuit closed, 45 remotely controlled means for causing said holding means to move into such holding position, and automatic means operable to 50 open the motor circuit during gas making operations without affecting the positioning of the said holding means.
- 10 5. Apparatus of the character described, comprising a gas producer adapted to contain a fuel bed of carbonaceous material, motor driven means for blasting said fuel bed to cause the generation of a combustible 55 gas and for distributing said gas for use; and means for controlling the blasting of the producer, comprising a motor circuit, a 60 main switch in said motor circuit, a second switch in said motor circuit, manually controlled means for closing said motor circuit main switch, means operable to hold said motor circuit main switch closed, means for causing said holding means to move into such holding position, and automatic means for opening said second motor circuit switch without affecting the positioning of the said holding means when the pressure of the distributed gas rises above a predetermined normal and for acting on the holding means 65 to render such means inoperative to hold the motor circuit main switch closed when the pressure of the distributed gas falls to a predetermined point below normal, irrespective of the positioning of the second motor circuit switch.
- 10 6. Apparatus of the character described, comprising a gas producer adapted to contain a fuel bed of carbonaceous material, motor driven means for blasting said fuel bed to cause the generation of a combustible gas and for distributing said gas for use, a motor circuit comprising a main switch constructed to normally remain open, and a secondary switch which tends to normally assume a closed position, and means for controlling operation of the blasting means, comprising manually controlled means for closing the main motor circuit switch, means constructed for positioning to hold said main motor circuit switch closed, means for causing said holding means to move into such holding position, and automatic means for intermittently opening and closing the secondary motor circuit switch without affecting the positioning of the said holding means as the pressure of the distributed gas fluctuates above or below a predetermined 70 normal and for acting on the holding means for rendering such means inoperative to hold the main motor circuit switch closed when pressure falls to a predetermined point below normal.
- 10 7. Apparatus of the character described, comprising a gas producer adapted to contain a fuel bed of carbonaceous material, motor driven means for blasting said fuel bed to cause the generation of combustible 75 gas and for distributing said gas for use; and means for controlling operation of said blasting means comprising a motor circuit having two switches therein both of which must be closed for the motor to operate, 80 manually operable means for closing one switch, means for holding such switch closed, and pressure responsive means for opening and closing the other switch without affecting the setting of the said one switch.
- 10 8. Apparatus of the character described, comprising a gas producer adapted to contain a fuel bed of carbonaceous material, motor driven means for blasting said fuel 85

bed to cause the generation of combustible gas and for distributing said gas for use; and means for controlling operation of said blasting means, comprising a motor circuit having two switches therein both of which must be closed for the motor to operate, manually controlled electrical means for closing one switch, pressure means responsive to pressure of generated gas for holding such one switch closed, and other means for opening and closing the other switch without affecting the setting of the said one switch.

9. Apparatus of the character described, comprising a gas producer adapted to contain a fuel bed of carbonaceous material, motor driven means for blasting said fuel bed to cause the generation of combustible gas and for distributing said gas for use; and means for controlling operation of said blasting means comprising a motor circuit having two switches therein both of which must be closed for the motor to operate, manually controlled means for closing one switch, means for holding such one switch closed, pressure responsive means for retaining the holding means in such switch holding position so long as the delivery pressure of the gas exceeds a predetermined minimum, other pressure responsive means for opening and closing the other switch as the pressure of the delivered gas fluctuates above or below a predetermined normal without affecting the setting of the said one switch, said other pressure responsive means being adapted to close the other switch before the pressure falls sufficiently to render the said holding means inoperative to hold the one switch closed, and manually controlled means for opening said one switch against the action of said holding means.

10. Gas generating apparatus of the character described, comprising a gas generator, a pump for delivering the generated gas to a distributing line, an electric circuit for operating said pump, and control means for said circuit comprising a container for receiving an electrolyte, an electrode extending into said container for normal contact with the electrolyte, a second spaced electrode extending into said container, and means for subjecting the electrolyte to the pressure in the distributing line to cause its movement into or out of contact with the said second electrode.

11. Gas generating apparatus of the character described, comprising a gas generator, a pump for delivering the generated gas to a distributing line, an electric circuit for operating said pump, and control means for said circuit comprising a container for receiving an electrolyte, an electrode extending into said container for normal contact with the electrolyte, a second spaced electrode extending into said container and ter-

minating in a face substantially parallel with the normal surface of the electrolyte, and means for subjecting the electrolyte to the pressure in the distributing line to cause its movement into or out of contact with the said second electrode. 70

12. Gas generating apparatus of the character described, comprising a gas generator, a pump for delivering the generated gas to a distributing line, an electric circuit for operating said pump, a main switch in said circuit, and an auxiliary switch in said circuit comprising a container for receiving an electrolyte, an electrode extending into said container to be normally in contact with said electrolyte, a second spaced electrode extending into the container and terminating in a face substantially parallel with the normal surface of the electrolyte, and means for subjecting the electrolyte to the pressure in the distributing line to cause its movement into or out of contact with the said second electrode, the electrolyte being of such character that it will adhere to and wet the second electrode. 80

13. Gas generating apparatus of the character described, comprising a gas producer, a pump for causing operation of said producer to generate a combustible gas, a valve casing connected to the outlet side of said pump, a distributing line leading off from said casing, a vent pipe leading off from said casing, a valve within said casing tending to move toward position to close off the distributing line from the outlet of the pump, means for moving said valve to open connection between the distributing line and the pump outlet and for closing connection between the vent pipe and the pump outlet, the pressure of the gas flowing through the valve casing serving to hold the said valve in such operative position so long as the pressure exceeds a predetermined amount, an electric circuit for operating the said pump, a main switch in said circuit, means responsive to pressure conditions within the distributing line for maintaining the said main switch in position to hold the electric circuit closed so long as that pressure exceeds a predetermined amount and to cause 100

opening of the main switch to break the electric circuit when the pressure falls below such predetermined amount, an auxiliary switch in said circuit comprising an electrode and an electrolyte, and means for subjecting the electrolyte to pressure within the valve casing to cause opening or closing of said auxiliary switch. 110

14. Gas generating apparatus of the character described comprising a gas producer, a pump for causing operation of said producer to generate a combustible gas, a valve casing connected to the outlet side of said pump, a distributing line leading off from said casing, a vent pipe leading off from said 120

casing, a valve within said casing tending to move toward position to close off the distributing line from the outlet of the pump, means for moving said valve to open connection between the distributing line and the pump outlet and for closing connection between the vent pipe and the pump outlet, the pressure of the gas flowing through the valve casing serving to hold the said valve in such operative position so long as the pressure exceeds a predetermined amount, an electric circuit for operating the said pump, a main switch in said circuit, means responsive to pressure conditions within the distributing line for maintaining the said main switch in position to hold the electric circuit closed so long as the pressure exceeds a predetermined amount and to cause opening of the main switch to break the electric circuit when the pressure falls below such predetermined amount, an auxiliary switch in said circuit comprising an electrode and an electrolyte, and means for subjecting the electrolyte to the pressure within the valve casing to cause opening or closing of said auxiliary contact, said electrode terminating in a flat face arranged substantially parallel to the working surface of the electrolyte.

15. Apparatus of the character described, comprising, in combination, a gas producer adapted to contain a fuel bed of carbonaceous material, a pump for blasting said fuel bed to cause the generation of gas and for distributing said gas for use, an electric motor for driving said pump, an electric circuit for said motor, a pressure actuated liquid conducting switch within said motor circuit, said switch having relatively movable contacts and conducting liquid responsive to small pressure variations within said generated gas and adapted to break contact between said contacts and conducting liquid at a predetermined pressure, said motor when energized operating at a speed in excess of that required to maintain said predetermined pressure, whereby the switch is intermittently actuated to make and break the motor circuit to thereby drive said motor to maintain a substantially constant pressure.

16. Apparatus of the character described, comprising a gas producer adapted to contain a fuel bed of carbonaceous material, motor operated means for blasting said fuel bed to cause the generation of combustible gas and for delivering said gas under pressure, an electric circuit for said motor, a switch within said circuit adapted to control the operation of said motor when gas is generated for use, and means for causing intermittent operation of said motor during stand-by periods when said motor circuit switch is open, said means comprising a shunt motor circuit around said motor circuit

circuit switch, and a second switch within said shunt circuit.

17. Apparatus of the character described, comprising a gas producer adapted to contain a fuel bed of carbonaceous material, 70 motor operated means for blasting said fuel bed to cause the generation of gas and to distribute said gas for use, and automatic means for causing intermittent operation of said motor during stand-by periods when gas is 75 not being generated for use to thereby keep said fuel bed in gas making condition, said automatic means comprising an electrolytic switch within said circuit including a container for electrolyte, an electrode within 80 said electrolyte, a pressure tube dipping within said electrolyte, a second electrode within said pressure tube, means for building up a gas pressure within said pressure tube during operation of said motor to thereby depress said electrolyte below said electrode to open said motor circuit, and means for effecting the slow leakage of gas from 85 said pressure tube to cause said electrolyte to again contact with said electrode to close the 90 motor circuit after a predetermined time interval.

18. A gas generating apparatus of the character described, comprising a gas producer, a pump for causing operation of said 95 producer to generate combustible gas, a valve casing connected to the outlet side of said pump, a distributing line leading off from said casing, a vent pipe leading off from said casing, a valve within said casing 100 tending to move toward position to close off the distributing line from the outlet of the pump, and means for moving said valve to open connection between the distributing line and the pump outlet and for closing connection between the vent pipe and the pump outlet, said valve in its moved position being so subjected to the pressure of the gas flowing through the valve casing that this pressure will hold the said valve 105 in such operative position so long as the pressure exceeds a predetermined amount, said moving means releasing said valve after said movement whereby when the pressure of the gas in said valve casing falls below 110 said predetermined amount said valve returns to its original position to open connection between the vent pipe and pump outlet and close connection between the distributing line and the pump outlet.

19. A gas generating apparatus of the character described, comprising a gas producer, a pump for causing operation of said producer to generate combustible gas, a valve casing connected to the outlet side of said pump, a distributing line leading off from said casing adapted in one position to close communication between the pump and the distributing line and in another position to close communication between the pump 125 130

and the vent pipe, a vent pipe leading off from said casing, a valve within said casing, a work device connected to said distributing line to receive gas distributed by said pump, 5 said work device being remotely positioned with respect to said gas producer and valve casing, and remote manual electrical control means positioned adjacent said work device for controlling the position of said 10 valve to control the communication of said pump outlet with said distributing line or said vent pipe respectively.

20. Apparatus of the character described, comprising a gas producer adapted to contain a fuel bed of carbonaceous material, 15 motor driven means for blasting said fuel bed to cause the generation of combustible gas and for distributing said gas for use, and means for controlling the operation of 20 said motor driven blasting means, comprising a motor circuit having two switches therein both of which must be closed for the motor to operate, manually controlled means for closing one switch, means for 25 holding such one switch closed, pressure responsive means for retaining said holding means in such switch holding position so long as the delivery pressure of the gas exceeds a predetermined minimum, manually 30 controlled means for moving said holding means out of switch holding position against the action of said pressure responsive means to effect opening of said one switch, and other means for opening and closing the 35 other switch without affecting the setting of the said one switch.

21. A gas generating system of the character described, comprising a gas producer, a blower for blasting the fuel bed in said 40 producer to generate combustible gas and for delivering said gas for use, an electric motor for driving said blower, and relay switch mechanism for controlling the operation of said blower, said switch mechanism comprising a pair of switch contacts in the motor circuit normally tending to remain open, means for closing said switch contacts, and holding means responsive to pressure of generated gas for holding said contacts closed as long as said pressure exceeds a 45 predetermined minimum.

22. A gas generating system of the character described, comprising a gas producer, a blower for blasting the fuel bed in said 50 producer to generate combustible gas and for delivering said gas for use, an electric motor for driving said blower, and relay switch mechanism for controlling the operation of said blower, said switch mechanism comprising a pair of switch contacts in the motor circuit normally tending to remain open, manually controlled electric means for closing said switch contacts, holding means responsive to pressure of generated gas for 55 holding said contacts closed as long as said

pressure exceeds a predetermined minimum, and manually controlled electric means for effecting opening of said switch contacts against the action of said pressure responsive holding means. 70

23. A domestic gas generating apparatus of the character described, comprising a small size gas producer adapted to contain a fuel bed of carbonaceous material, means for blasting said fuel bed to cause the generation of a combustible gas and for distributing said gas for use, a domestic work device such as a gas stove remotely positioned with respect to said gas producer, a delivery main for supplying gas from said producer to 80 said work device, remote control means positioned adjacent said work device for initiating operation of said blasting means, control means functioning automatically to control said blasting means after initiation thereof and during gas generation, and other remote control means positioned adjacent said work device for terminating operation of said blasting means. 85

24. A domestic gas generating apparatus of the character described, comprising a small size gas producer adapted to contain a fuel bed of carbonaceous material, means for blasting said fuel bed to cause the generation of a combustible gas and for distributing said gas for use, a domestic work device such as a gas stove remotely positioned with respect to said gas producer, a delivery main for supplying gas from said producer to 90 said work device, remote control means positioned adjacent said work device for initiating operation of said blasting means, control means functioning automatically to control said blasting means after initiation thereof and during gas generation, and other remote control means positioned adjacent said work device for terminating operation of said blasting means. 95

25. A gas generating apparatus of the character described, comprising a gas producer, a pump for causing operation of said

producer to generate combustible gas, a distributing pipe connected to said producer, a vent pipe connected to said producer, valve means for closing off communication of said producer with said distributing pipe and for closing off communication of said producer with said vent pipe, an electromagnet for operating said valve means, an electrical circuit for said electromagnet, and a manually operable switch in the electrical circuit of said electromagnet to manually control energization of said electromagnet to thereby shift said valve means to close off communication of the producer with one of said pipes and open communication of the pro- 125

ducer with the other of said pipes at the will of the operator.

26. A gas generating apparatus of the character described, comprising a gas producer, a pump for blasting said producer to generate combustible gas, an electric motor for operating said pump, an electrical circuit for said motor, a switch therein, a distributing line connected to said producer for the generated gas, a member responsive to pressure of generated gas in said distributing line for holding said switch closed, said member being automatically releasable when the pressure of the generated gas is below a predetermined minimum, and means for opening said switch upon release of said pressure responsive member.

27. A gas generating apparatus of the character described, comprising a gas producer, a pump for blasting said producer to generate combustible gas, an electric motor for operating said pump, an electrical circuit for said motor, a distributing line connected to said producer for the generated gas, pressure operated mechanism responsive to pressure of generated gas within said distributing line for temporarily opening said electrical circuit when the pressure of the generated gas exceeds a predetermined normal and for reclosing said electrical circuit when the pressure falls below predetermined normal, and a second pressure operated mechanism responsive to the pressure of generated gas within said distributing line for automatically opening said electrical circuit when the pressure of generated gas falls to a predetermined minimum below said predetermined normal pressure.

28. A domestic gas generating apparatus of the character described, comprising a small size gas producer adapted to contain a fuel bed of carbonaceous material, means for blasting said fuel bed to cause the generation of a combustible gas and for distributing said gas for use, a domestic work device such as a gas stove remotely positioned with respect to said gas producer, a delivery main for supplying gas from said producer to said work device, remote control means positioned adjacent said work device for initiating operation of said blasting means, control means functioning automatically to control said blasting means after initiation thereof and during gas generation, other remote control means positioned adjacent said work device for terminating operation of said blasting means, and pressure operated mechanism responsive to pressure of generated gas within said delivery main for automatically terminating operation of said blasting means when the pressure of generated gas within said delivery main falls to a predetermined minimum.

29. Gas generating apparatus of the char-

acter described, comprising a gas producer, a pump for blasting said producer to generate combustible gas, power means for operating said pump, control mechanism for said power means including a member for causing operation of the power means and for terminating operation thereof, a distributing line connected to said producer, pressure operated mechanism responsive to pressure of generated gas within said distributing line for holding said member in position to cause operation of said power means, said pressure operated mechanism being automatically releasable when the pressure of the generated gas within said distributing line is below a predetermined minimum, and means for actuating said member upon release of said pressure operated mechanism to thereby automatically terminate operation of the said power means.

30. Gas generating apparatus of the character described, comprising a gas producer adapted to contain a fuel bed of incandescent solid carbonaceous fuel, a pump for blasting said fuel bed to generate combustible gas, an electric motor driving said pump, an electrical circuit for said motor, an electrical power line, connections between said electrical power line and said electrical motor circuit for supplying electrical energy thereto, a switch within said electrical motor circuit, and mechanism responsive to a failure in the supply of electrical energy from said power line to said electrical motor circuit for automatically opening said switch.

31. A gas generating apparatus of the character described such as adapted for domestic use, comprising a small size gas producer, a pump for blasting the producer to generate combustible gas, power means for operating said pump, a distributing line connected to said producer, a work device connected to said distributing line, control mechanism for controlling the operation of said power means during the supplying of generated gas to said work device, and additional control mechanism operable during standby periods when use of generated gas at said work device is temporarily discontinued for automatically and intermittently actuating said power means for brief intervals to thereby maintain said fuel bed in gas making condition during such standby periods.

32. A gas generating apparatus of the character described such as adapted for domestic use, comprising a small size gas producer, a pump for blasting the producer to generate combustible gas, an electric motor for operating said pump, an electrical circuit for said motor, a distributing line connected to said producer, a work device connected to said distributing line, pressure operated mechanism responsive to pressure of

generated gas within said distributing line during the supplying of generated gas to said work device for temporarily opening said electric circuit to stop operation of the
5 motor driven pump when the pressure of generated gas within said distributing line exceeds a predetermined normal and for re-closing said electrical circuit to restart the motor driven pump when the pressure falls
10 below predetermined normal, and additional control mechanism automatically operable during standby periods when use of generated gas at said work device is temporarily discontinued for intermittently opening and
15 closing said electric circuit at brief intervals for intermittently operating said motor driven pump to blast the producer at brief intervals to thereby maintain said fuel bed in gas making condition during such stand-
20 by periods.

33. Apparatus of the character described, comprising in combination, a gas producer adapted to contain a fuel bed of carbonaceous material, a gas offtake for said producer, a pump for effecting blasting of said fuel bed having a suction side connected to said gas offtake and a pressure discharge side, a gas distribution conduit connected to the said discharge side of said pump, an
25 electric motor for driving said pump, the said electric motor when energized being adapted to drive said pump at a rate in excess of that required to maintain a predetermined gas pressure within said gas distribution conduit, an electric circuit for said motor, a sensitive switch having parts of small inertia within said motor circuit, and means responsive to pressure within said gas distribution conduit for actuating said
30 switch to intermittently make and break said motor circuit in accordance with small pressure fluctuations at a rate such that the inertia of said motor and pump moving parts maintains the said parts in motion
35 during the periods of intermittent deenergization of said motor, the said motor and pump parts thereby operating at a rate less than their rate of operation when continuously energized and such as to maintain a substantially constant pressure within said
40 gas distribution conduit.

In testimony whereof I hereto affix my signature.

HARRY F. SMITH.

CERTIFICATE OF CORRECTION.

Patent No. 1,823,382.

Granted September 15, 1931, to

HARRY F. SMITH.

It is hereby certified that error appears in the printed specification of the above numbered patent requiring correction as follows: Page 12, line 127, claim 19, after "casing" insert , a vent pipe leading off from said casing, a valve within said casing, and page 13, lines 1 and 2, same claim, strike out "a vent pipe leading off from said casing, a valve within said casing,"; and that the said Letters Patent should be read with this correction therein that the same may conform to the record of the case in the Patent Office.

Signed and sealed this 3rd day of November, A. D. 1931.

(Seal)

**M. J. Moore,
Acting Commissioner of Patents.**
